UNITED STATES PATENT OFFICE.

GEORGE A. LOWRY, OF MALDEN, MASSACHUSETTS.

PROTECTIVE APPARATUS FOR ORCHARDS, GARDENS, AND THE LIKE.

1,035,980.

Specification of Letters Patent. Patented Aug. 20, 1912.

Application filed July 10, 1911. Serial No. 637,683.

To all whom it may concern:

Be it known that I, GEORGE A. LOWRY, a citizen of the United States, and resident of Malden, in the county of Middlesex and 5 State of Massachusetts, have invented new and useful Improvements in Protective Apparatus for Orchards, Gardens, and the Like, of which the following is a specification.

10 The primary function of this apparatus is to produce and maintain heat and dense smoke in orchards and gardens which are sensitive and occasionally exposed to frost, though the construction of the fuel distributing system is such that with easy readjustment it can be employed for irrigation or spraying. These objects, particularly the preservation of the orchard or garden from frost are attained with economy of fuel and 20 labor for reasons which will transpire.

In the drawings hereto annexed which illustrate an example of my invention, Figure 1 represents, in perspective, the general arrangement of the protective system; 25 Fig. 2 is a detail, showing a fuel pipe, fire pan, and holding clip in cross section; Fig. 3 is a detail similar to Fig. 2, showing a fire pan removed from the holding clip; Fig. 4 is a detail showing one of the fuel 30 taps in longitudinal section; and Fig. 5 is a detail on a larger scale, showing a section of the tap-plug, on line 5—5 of Fig. 4.

The apparatus comprises a fuel tank marked A, the fuel employed being preferably crude petroleum or some other cheap liquid fuel. In order to insure the proper fluidity of the fuel, a heater B is placed near the tank A, this heater containing a coil B' with a circulating return B² so that 40 the fuel is warmed not only in the coil but in the tank A also. A main pipe C provided with a controlling valve or shut off C' lead from the coil B' across the orchard or garden and from the pipe C distributing 45 pipes D branch off at proper intervals. These distributing pipes are supported as by metal stakes E and at suitable intervals are provided with taps at F. These taps consist of ordinary T connections which 50 screw to the pipe D at F' and are provided with plugs G threaded into the lateral branches of the T's, these plugs being preferably composed of brass or other non-corrodible metal. The threaded plugs G have 55 each a lateral slit g about a thirty-second of an inch in width, the back wall of the

slit extending diagonally downward so that the slits increase in section downwardly. At the top of the plug which is squared as at g' the clip H is placed, this clip being 60 provided with resilient hooked ends h to receive and retain the fire pan I when the latter is not in use to receive fuel. The clips H thus perform the function of wrenches to turn the plug G up or down and thus to 65 regulate the size of the fuel aperture provided by the slit g.

When the apparatus is prepared for use the tank A is filled with liquid fuel, the valve C' closed and the fire pans I are secured upside down in the clips H so as to shelter the taps F and the priming fuel J which is some easily inflammable material such as oakum tied to the pipes D loosely with inflammable cord which will allow the 70 primers J to fall as soon as the securing cord burns. Ordinarily, the plugs G will be so set that only every alternate plug is open for the egress of fuel.

When the temperature of the air has 80 fallen to a threatening point, a fire is started in the heater B so as to warm up the fuel in the coil B' and tank A. When the danger point of frost is approached or reached a gang of men provided with torches is stationed in the orchard or garden, the valve C' is opened and the men proceed to remove the fire pans I from the clips H placing them under the fuel outlets and igniting the primers J which first warm the pipes in the 85 neighborhood of the fuel outlets and then fall to the pans I where they ignite the fuel which presently emerges from the outlets g and drips into the pans. The pans being shallow and the supply of oil coming in 90 regular isolated quantities, there is no opportunity for a large body of oil to become heated so as to give off gases at high temperature which burn with a small amount of smoke. The shallow pans give a maximum of dense black smoke which, as much as the heat evolved, serves to protect the vegetation from frost, since it acts as a blanket to retain the earth-heat and the heat of the plants themselves in the orchard or 95 garden. The vegetation itself is kept warm by this same protective agency independently or in addition to the actual raising of the temperature by means of the fuel burned in the fire pans.

100 The location of the fuel outlets at the top of the T's F is important since in this 110

position soot does not collect at the outlets to clog them as it would if these were placed on the under side of the unions.

Should the weather require it the intervening unlighted fire pans may be started in the same way while the combustion from the originally started pans is in progress.

Should it be desired to increase the flow of oil the clips H can be given a half or quarter turn very rapidly, the men passing from one to the other without having to place and remove a wrench.

If at any time it is desired to drain the pipes of oil fuel the T's F can simply be given a half turn downward.

To use the pipe system as an irrigation or spraying apparatus, the nozzle plugs g are adjusted so as to direct a stream upon the tree or plant adjacent, the shut off valve C' is closed and the branch connection M placed in communication with a water supply or pump. The clips H are so placed as to lie transverse to the slit g so that when the apparatus is used to irrigate or spray the 25 clips will not interfere with the jets.

By means of this apparatus the protective combustion need not be started until the last minute, the fuel conveys itself automatically instead of having to be carried in barrels or cans, much less fuel is used than according to the methods heretofore practised, and when the atmospheric temperature has ceased to endanger the crop the operation can be instantly checked.

35 What I claim and desire to secure by Letters Patent is:

1. In protective apparatus for orchards, gardens, and the like, the combination of a reservoir adapted to contain liquid fuel, a 40 pipe system in communication with the reservoir, regulable taps at intervals in the pipe system comprising apertures directed upward, and fire pans below, and unconnected with the taps.

45 2. In protective apparatus for orchards, gardens and the like, the combination of a reservoir adapted to contain liquid fuel, a pipe system in communication with the reservoir, regulable taps at intervals in the 50 pipe system consisting of T's threaded to the pipes of the system, with threaded branches extending upward, and threaded plugs in said branches, each plug slotted laterally, the slots increasing in section downwardly, and fire pans at the taps.

55 3. In protective apparatus for orchards, gardens and the like, the combination of a reservoir adapted to contain liquid fuel, a pipe system in communication with the reservoir, regulable taps at intervals in the 60 pipe system, pan-clips mounted adjacent to each tap, and fire-pans adapted to be held inverted by the clips on the taps.

65 4. In protective apparatus for orchards, gardens and the like, the combination of a

reservoir adapted to contain liquid fuel, means to heat the fuel at the reservoir, a pipe system in communication with the reservoir, regulable taps at intervals in the pipe system, pan clips mounted adjacent to each tap, and fire pans adapted to be held inverted by the clips on the taps.

5. In protective apparatus for orchards, gardens and the like, the combination of a reservoir adapted to contain liquid fuel, a 75 pipe system in communication with the reservoir, regulable taps at intervals in the pipe system, consisting of T's threaded to the pipes of the system having fuel apertures on their upper portions, pan-clips 80 mounted adjacent to each tap, and fire-pans adapted to be held inverted by the clips on the taps.

6. In protective apparatus for orchards, gardens and the like, the combination of a 85 reservoir adapted to contain liquid fuel, a pipe system in communication with the reservoir, regulable taps at intervals in the pipe system consisting of T's threaded to the pipes of the system, with threaded branches extending upward, and threaded plugs in said branches, each plug slotted laterally, the slots increasing in section downwardly, pan-clips secured like keys to the threaded plugs, and fire-pans adapted to 95 be held inverted by the clips on the taps.

7. In protective apparatus for orchards, gardens and the like, the combination of a reservoir adapted to contain liquid fuel, a pipe system in communication with the reservoir, regulable taps at intervals in the pipe system, a normally closed branch pipe between the reservoir and the pipe system, adapted to connect with an alternative fluid-supply, and a cut off between said branch 105 and the fuel reservoir.

8. In protective apparatus for orchards, gardens and the like, the combination of a reservoir adapted to contain liquid fuel, a pipe system in communication with the reservoir, regulable taps at intervals in the pipe system, fire-pans at the taps, and readily inflammable priming material secured to the pipes at the taps.

9. In protective apparatus for orchards, 115 gardens and the like, the combination of a reservoir adapted to contain liquid fuel, means to heat the liquid fuel at the reservoir, a pipe system in communication with the reservoir, regulable taps at intervals in the 120 pipe system, fire-pans at the taps, and readily inflammable priming material secured to the pipes at the taps.

10. In protective apparatus for orchards, 125 gardens and the like, the combination of a reservoir adapted to contain liquid fuel, a pipe system in communication with the reservoir, regulable taps at intervals in the pipe system, consisting of T's threaded to the pipes of the system having fuel aper-

tures on their upper portions, fire-pans at the taps, and readily inflammable priming material secured to the pipes at the taps.

11. In protective apparatus for orchards, gardens and the like, the combination of a reservoir adapted to contain liquid fuel, a pipe system in communication with the reservoir, regulable taps at intervals in the pipe system, consisting of T's threaded to 10 the pipes of the system, with threaded branches extending upward and threaded

plugs in said branches, each plug slotted laterally, the slots increasing in section downwardly, fire-pans at the taps, and readily inflammable priming material secured to the 15 pipes at the taps.

Signed by me at Boston, Massachusetts, this first day of July 1911.

GEORGE A. LOWRY.
